UNITED STATES PATENT OFFICE.

GEORGE P. NIELSEN, OF WHITESTONE, NEW YORK.

ROTARY ENGINE.

SPECIFICATION forming part of Letters Patent No. 693,055, dated February 11, 1902.

Application filed October 1, 1901. Serial No. 77,196. (No model.)

To all whom it may concern:

Be it known that I, GEORGE P. NIELSEN, a citizen of the United States, residing at Whitestone, Long Island, in the county of Queens 5 and State of New York, have invented certain new and useful Improvements in Rotary Engines, of which the following is a full and complete specification, such as will enable those skilled in the art to which it appertains to 10 make and use the same.

The object of this invention is to provide a rotary engine which is simple in construction and operation and is strong and durable and which possesses great power in proportion to 15 the amount of steam employed and which will not get out of order or frequently need repair; and with this and other objects in view the invention consists in a rotary engine constructed as hereinafter described and claimed.

20 In the drawings forming part of this specification, in which the separate parts of my improvement are designated by the same reference characters in each of the views, Figure 1 is a partial sectional side elevation of a rotary engine constructed according to my invention, the plane of the section being designated by the line xx in Fig. 2; Fig. 2, a partial section on the line yy of Fig. 1; Fig. 3, a 25 partial transverse section on the line zz of Fig. 1; Fig. 4, a plan view of two sets of valves which I employ, and Fig. 5 a perspective view of a detail of the construction.

In the practice of my invention I provide 30 a cylindrical casing a , consisting of two similar side pieces a^2 , which are circular in form and which are rigidly and permanently connected by a band or rim b , bolted or otherwise secured to side flanges a^3 , with which the sides a^2 of the casing are provided, and the 35 sides a^2 of the casing a are each provided on its inner face with an inwardly-directed flange or rim a^4 , by means of which an annular steam-chamber a^5 is formed within the casing a and within which is a central chamber a^6 , and passing transversely through the casing and through the central chamber a^6 is a shaft c , to which is secured a central circular disk or plate d , provided with a hub d^2 , through which the shaft c passes. The disk or plate 40 e is of the same diameter as the outer diameter of the inwardly-directed rims or flanges a^4 , by means of which the annular steam-

chamber a^5 and the central chamber a^6 are formed, and formed in the inner face of the annular flanges or rims a^4 are annular grooves 55 a^7 , in which are placed annular packing-rings which are forced inwardly against the disk or plate by the springs e^2 .

The band b of the casing a is preferably made of two parts, as shown in Fig. 1, and 60 provided at its opposite sides with radial plates b^2 , which are bolted together and also secured to suitable supports, one of which is shown at b^3 , this construction being clearly 65 shown in Fig. 1, and secured to the top portion of said casing or the band b thereof is an upwardly-directed and preferably-inclined supplemental casing g , composed of two parts g^2 and in the top of which is a steam-chamber g^3 , closed by a plate g^4 , through which 70 passes a steam-pipe g^5 . The separate parts g^2 of the supplemental casing g or the side walls thereof are quite thick, as shown in Fig. 1, and in practice, in addition to being bolted to the rim or band b of the casing a , as shown 75 at g^6 in Fig. 1, are also bolted together by means of side lugs or projections g^7 , with which each of said parts are provided, two of these lugs or projections being shown in 80 Fig. 2.

Between the separate parts g^2 of the supplemental casing g is a longitudinal chamber h , and formed in the rim or band b is a passage h^2 , communicating therewith, and in the upper portion of said parts g^2 of the supplemental casing g is a passage h^3 , which forms 85 a communication between the steam-chamber g^3 and the chamber h , and mounted in the chamber h and movable in the passages h^2 and h^3 is a slide h^4 , the lower end of which is 90 beveled at its opposite sides, as shown at h^5 , and the said walls of the separate parts g^2 of the casing g are provided in the passage h^3 with spring-actuated packings h^6 , which bear on said slide, and in the rim or band b at the 95 opposite sides of the passage h^2 are similar spring-actuated packings h^7 , which also bear on said slide.

Secured to the disk or plate d , having the hub d^2 , through which the shaft c passes, is 100 a triangular piece or block d^3 , which may be formed integrally with said disk or plate, if desired, and which serves as a piston, which moves in the annular steam-chamber a^5 , and

said block d^3 is also provided at its outer edge with a spring-actuated packing d^4 . The piston-block d^3 is of such dimensions as to exactly fill or fit the annular steam-chamber a^5 and to move therein and is carried around in said annular steam-chamber by the disk or plate d as the shaft c is revolved.

Mounted in or passing through the side walls of the chamber h , formed in the parts g^2 of the supplemental casing g , and at the top and bottom portions of said chamber are two sets of shafts the separate members of which are designated, respectively, by the reference characters i and i^2 , and these shafts are provided with antifriction-rollers i^3 , which bear on the slide h^4 , and at the opposite sides of the supplemental casing g and at the bottom thereof are a plurality of steam ports or passages k and k^2 , (shown in dotted lines in Fig. 1,) which extend inwardly and downwardly and open at the bottom of the passage h^2 , through which the slide h^4 passes. The steam ports or passages k at one side are controlled by a cylindrical valve k^3 and the ports or passages k^2 at the opposite side are controlled by a valve k^4 .

At each side of the supplemental casing g the separate parts thereof are provided with a plurality of vertically-arranged steam ports or passages k^5 and k^6 , respectively, and these ports or passages communicate with the steam-chamber g^3 and extend downwardly, and each of the passages k^5 communicates with one of the corresponding ports or passages k , while each of the ports or passages k^6 communicates with one of the corresponding ports or passages k^2 , and the ports or passages k^5 are all controlled by a cylindrical slide-valve k^7 , while the ports or passages k^6 are all controlled by a cylindrical slide-valve k^8 . The ports or passages k^5 and k^6 are shown in dotted lines in Fig. 1 and in cross-section in Fig. 3, and the valves k^3 and k^4 are connected at one end by a plate m , (shown in dotted lines in Fig. 1 and in full lines in Fig. 4,) and the valves k^4 and k^8 are connected at the same end by a plate m^2 , (shown in dotted lines in Fig. 1 and in full lines in Fig. 4,) and secured to these plates m and m^2 are other plates m^3 , provided each with an outwardly-directed arm m^4 , to which is pivoted at m^5 a yoke m^6 , provided with an upwardly-directed lever m^7 , which is pivoted at m^8 to an arm m^9 , which is secured to the adjacent side of the supplemental casing g or to one part thereof, and by means of the lever m^7 the valves k^3 and k^4 and k^8 , which are arranged in pairs, may be moved longitudinally or transversely of the supplemental casing, so as to open and close the ports or passages k , k^2 , k^5 , and k^6 , it being understood that each of said valves is provided with a transverse passage for each of said ports or passages.

The operation will be readily understood from the foregoing description when taken in connection with the accompanying drawings and the following statement thereof.

It will be apparent from the foregoing description that this rotary engine is reversible, the main power-shaft c being capable of being driven in either direction, and this operation results from the arrangement of the steam ports or passages k and k^2 on one side of the supplemental casing g , the corresponding steam ports or passages k^3 and k^6 on the other side of the double arrangement of slide-valves which controls these ports or passages, and the form of the piston-block d^3 and the slide h^4 , which operates in connection therewith. Suppose it be desired to turn the main shaft c to the left when viewed in the position shown in Fig. 1. The steam is admitted through the steam-supply pipe g^5 and the ports or passages k and k^5 are open and in communication in such manner that the steam is admitted therethrough to the left of the slide h^4 . In this position of the parts the outer ends of the steam ports or passages k are closed, and the steam ports or passages k^3 at the opposite side of the supplemental casing are open, the ports or passages k^6 at said side being closed. As the steam enters the annular steam-chamber a^5 at the left of the slide h^4 in the position of the parts shown in Fig. 1 the power-shaft c is revolved to the left, the piston-block d^3 moving in the direction of the arrow r , and as the said shaft and piston-block revolve the slide h^4 passes downwardly over the right-hand side of the piston-block until it strikes the outer wall of the chamber a^6 , in which position it entirely closes the annular chamber a^5 . As the shaft c continues to revolve the slide h^4 is raised by the opposite beveled side of the piston-block, and as the piston-block passes beneath said slide the inner end thereof is flush with the inner entrance to the passage h^2 , and, as will be understood, the shaft c continues to revolve, and the slide h^4 again repeats the above-described operation, said slide passing over the piston-block d^3 at each revolution of the shaft c and moving radially at all times. At each revolution of the shaft c the exhaust-steam passes out through the ports or passages k^2 , which are open during this operation, and at each revolution of the shaft c , when the piston-block d^3 is in the position shown in Fig. 1, fresh steam enters through the ports or passages k and operates upon the right-hand side of the piston-block d^3 and continues the revolution of the shaft c . When it is desired to reverse the movement of the piston-shaft, the ports or passages k^6 and k^2 , which communicate with the annular chamber a^5 , are open, the outer ends of the ports or passages k^2 being closed, while the ports or passages k on the opposite side are open to admit of the exhaust of the steam. The valves k^3 k^4 and k^7 k^8 , which are arranged in pairs, as hereinbefore described, are operated simultaneously by the movement of the lever m^7 , and only a slight movement is necessary for these valves in order to accomplish the desired result.

Having thus fully described my invention,

what I claim as new, and desire to secure by Letters Patent, is—

1. A rotary engine comprising a circular casing provided with a central circular chamber and an annular steam-chamber inclosing the same, a shaft passing centrally through the central chamber and provided within said chamber with a disk or plate, the perimeter of which passes through the annular wall of the central chamber, a piston-block connected with the perimeter of said disk or plate and movable in the annular steam-chamber, a supplemental casing connected with one side of the first-named casing and provided in its outer end with a steam-chamber and means for admitting steam thereto, a steam-operated slide mounted centrally in said supplemental casing radially of the first-named casing and extending into the annular steam-chamber, steam ports or passages in the opposite sides of the supplemental casing and in communication with said steam-chamber, valves for controlling the said ports or passages, other steam ports or passages also in the opposite sides of the supplemental casing and in communication with the first-named ports or passages and with the annular steam-chamber at the opposite sides of said slide, said last-named ports or passages being so formed as to open outwardly through the sides of the supplemental casing and being also provided outside of their communication with the first-named ports or passages with valves by which they are controlled, the valves in said ports or passages at each side of the supplemental casing being arranged in pairs and connected and longitudinally movable, substantially as shown and described.

2. A rotary engine comprising a circular casing, provided with a central circular chamber and an annular steam-chamber inclosing the same, a shaft passing centrally through the central chamber and provided within said chamber with a disk or plate, the perimeter of which passes through the annular wall of the central chamber, a piston-block connected with the perimeter of said disk or plate and movable in the annular steam-chamber, a supplemental casing connected with one side of the first-named casing and provided in its outer end with a steam-chamber and means for admitting steam thereto, a steam-

operated slide mounted centrally in said supplemental casing radially of the first-named casing and extending into the annular steam-chamber, steam ports or passages in the opposite sides of the supplemental casing and in communication with said steam-chamber, valves for controlling the said ports or passages, other steam ports or passages also in the opposite sides of the supplemental casing and in communication with the first-named ports or passages and with the annular steam-chamber at the opposite sides of said slide, said last-named ports or passages being so formed as to open outwardly through the sides of the supplemental casing and being also provided outside of their communication with the first-named ports or passages with valves by which they are controlled, the valves in said ports or passages at each side of the supplemental casing being arranged in pairs and connected and longitudinally movable, substantially as shown and described.

3. In a rotary engine, a circular casing provided with a central circular chamber and an annular steam-chamber surrounding the same, a shaft passing centrally through the central chamber and provided within said chamber with a disk or plate, the perimeter of which passes through the annular wall of said chamber and is provided with a piston-block movable in the annular steam-chamber, a supplemental casing connected with the circular casing at one side thereof and extending radially therefrom and provided centrally with a steam-operated slide movable in and radially of the annular steam-chamber, a steam-chamber within the supplemental casing and means for admitting steam therefrom to the annular steam-chamber at either side of said slide, substantially as shown and described.

In testimony that I claim the foregoing as my invention I have signed my name, in presence of the subscribing witnesses, this 30th day of September, 1901.

GEORGE P. NIELSEN.
